RAILWAY TRACK CIRCUIT APPARATUS

Robert M. Gilson, Pittsburgh, Pa., assignor to
 The Union Switch & Signal Company, Swiss-
 vale, Pa., a corporation of Pennsylvania

Application March 31, 1937, Serial No. 134,148

8 Claims. (Cl. 246—130)

My invention relates to railway track circuit apparatus and has for an object the provision of a simple form of track circuit having relatively high shunting sensitivity. A further object of my invention is the provision in apparatus of this character of means for providing improved highway crossing protection.

I shall describe one form of railway track circuit apparatus embodying my invention, and shall then point out the novel features thereof in claims.

The accompanying drawing is a diagrammatic view showing one form of track circuit apparatus embodying my invention, as applied to the control of apparatus at a highway crossing.

Referring to the drawing, the reference characters 1 and $1a$ designate the track rails of a stretch of railway track intersected by a highway H . Traffic may move over this stretch in either direction. The rails of this stretch of track are divided by insulated joints 2 to form rail sections $C—E$ and $E—F$ in the upper rail and rail sections $C—D$ and $D—F$ in the lower rail. Connected across the rail sections $C—E$ and $D—F$ through a current limiting device 4 , is a source of current 3 , conveniently illustrated as a battery. Connected across the rails at the one end of the stretch is a track relay Ta , and connected across the rails at the other end of the stretch is a second track relay Tb . Between rail sections $E—F$ and $C—D$ is connected a jumper 7 which completes the current path from source 3 to the track relays Ta and Tb .

It will be noted that the apparatus thus far described comprises a single track circuit which may be traced from one terminal of source 3 , limiting resistor 4 , wire 6 , rail 1 , track relay Ta , rail $1a$, jumper 7 , rail 1 , track relay Tb , rail $1a$, and wire 8 , to the other terminal of the source. By locating the rail joints 2 on opposite sides of the highway, certain advantages with respect to the operation of the highway crossing apparatus are obtained. These advantages will become apparent as the description progresses.

Track relays Ta and Tb control an interlocking relay R of the usual and well-known type. When one or the other of these track relays is deenergized, the circuit for the respective magnet Ra or Rb of the interlocking relay R is interrupted and an energizing circuit for a suitable highway crossing signal S becomes closed at back contact 9 or $9a$ of the interlocking relay.

When a train moving toward the right enters section $C—D$, track relay Ta will be released by the train shunt and will initiate operation of the

crossing signal S through the closing of back contact 9 of magnet Ra . The signal will continue to operate even after the rear end of the train has passed the rail joint at location D because the train shunt will continue to remain effective across the source 3 during the time that the train is occupying the highway intersection, as will be obvious from the drawing. It will be apparent, therefore, that a warning at the crossing will be provided during the full time that any part of the train occupies the highway intersection.

When the train passes beyond the rail joint at location E and completely clears the crossing, energy will be re-applied to track relay Ta over a circuit which may be traced from one terminal of source 3 , resistor 4 , wire 6 , rail 1 , track relay Ta , rail $1a$, jumper 7 , the train shunt from rail 1 to $1a$, and wire 8 , back to the other terminal of the source. It should be pointed out, of course, that the entry of the train into section $E—F$ causes the track relay Tb to become deenergized, and that this will usually take place before relay Ta picks up. Accordingly, back contact $9a$ will be prevented from closing due to the presence of the well-known mechanical interlocking (not shown) between the armatures of magnets Ra and Rb .

To avoid the possibility of relay Ta picking up before relay Tb releases, due, for example, to the passage of a fast, light weight car through the highway intersection, the track relays may be made slow pick-up in character to prevent prolonged operation of signal S under this condition. After the train clears section $E—F$, relay Tb will become energized and all of the apparatus will be restored to the condition in which it is illustrated.

The operation for a train entering section $E—F$ from right to left will be similar in all respects to that just described.

The high shunting sensitivity of the track circuit herein disclosed results from the fact that when a train enters the section, the flow of rail current is limited not only by the limiting resistor 4 but also by the resistance of the winding of the distant track relay.

It will be clear that the apparatus herein described is not limited to the control of highway crossing apparatus, as the track circuit embodying my invention may be employed wherever a track circuit of the center-fed type is desired. The connections 6 and 8 from source 3 and the rail joints at locations D and E need not be staggered provided that the source 3 is connected across non-adjacent rail portions, such as por-

tion C—E of the upper rail and D—F of the lower rail. There is, however, an advantage in staggering the rail joints at D and E even though the track circuit is not used in conjunction with 5 highway crossing protection. This is because a single car, high speed train passing from one section to the other will then be able to shunt the track relay for the leaving end of the track circuit before releasing the shunt on the track relay at the entering end of the track circuit, thus 10 making more certain that the entering track relay will not pick up before the leaving track relay has had an opportunity to release.

An advantage of apparatus embodying my invention is that a simple form of track circuit having high shunting sensitivity has been provided which, when applied to highway crossing protection, provides improved operation of the highway crossing apparatus.

20 Although I have herein shown and described only one form of apparatus embodying my invention, it is understood that various changes and modifications may be made therein within the scope of the appended claims without departing 25 from the spirit and scope of my invention.

Having thus described my invention, what I claim is:

1. In combination with a stretch of railway track intersected by a highway, an insulated 30 joint in one rail at one side of the highway, an insulated joint in the other rail at the other side of the highway, said two joints defining a right-hand and a left-hand track section, a source of current connected across the two rails 35 from one rail of said left-hand section to the other rail of said right-hand section, an electrical connection joining said one rail of the right-hand section with said other rail of the left-hand section, two track relays connected respectively across the two rails adjacent the two 40 ends of said stretch, and highway crossing apparatus controlled by said two track relays.

2. In combination with a stretch of railway track, a first insulated joint in one rail of said 45 section, a second insulated joint in the other rail of said section and in staggered relation with said first insulated joint, said two joints defining a right-hand and a left-hand track section, a source of current connected across the two rails 50 from one rail of said left-hand section to the other rail of said right-hand section, an electrical connection joining said one rail of the right-hand section with said other rail of the left-hand section, two track relays connected 55 respectively across the two rails adjacent the two ends of said stretch, and signaling apparatus controlled by said two track relays.

3. A track circuit comprising, in combination, 60 a section of railway track, a first insulated joint in one rail of said section, a second insulated joint in the other rail of said section, means for impressing a track voltage across the two rails of said section on opposite sides of said two insulated joints, means for electrically connecting the two rails on the remaining sides of said 65 two insulated joints, a first track relay receiving energy from the two rails to the left of said two insulated joints, and a second track relay receiving energy from the two rails to the right of said two insulated joints.

4. A track circuit comprising, in combination,

a section of railway track divided by an insulated joint in one rail and an insulated joint in the other rail to form a left-hand and a right-hand rail section, means for impressing a track voltage from one rail of said left-hand section to the other rail of said right-hand section, means for electrically connecting said one rail of the right-hand section with said other rail of the left-hand section, a first track relay receiving energy from said left-hand rail section, and a second track relay receiving energy from said right-hand rail section.

5. In combination, a section of railway track, an insulated joint dividing one rail of said section into a first and a second rail portion, an insulated joint dividing the other rail of said section into a third and a fourth rail portion, an electrical connection between said second and said third rail portions, two track relays one for each end of said section, a source of current; 20 and a track circuit for said section including said source, said connection, said four rail portions, and said two track relays all in series.

6. In combination, a section of railway track, a first insulated joint dividing one rail of said section into a first and a second rail portion, a second insulated joint in staggered relation with said first insulated joint and dividing the other rail of said section into a third and a fourth rail portion, an electrical connection between 30 said second and said third rail portions, two track relays one for each end of said section, a source of current; and a track circuit for said section including said source, said connection, said four rail portions, and said two track relays all in series.

7. In combination with a stretch of railway track over which traffic may move in either direction and a highway intersecting said track section, an insulated joint in one rail at one side 40 of the highway, an insulated joint in the other rail at the other side of the highway, said two joints defining a right-hand and a left-hand track section, means for impressing a track voltage across the two rails from one rail of 45 said left-hand section to the other rail of said right-hand section, means for electrically connecting said one rail of the right-hand section with said other rail of the left-hand section, a first track relay receiving energy from the rails 50 at one end of said stretch, a second track relay receiving energy from the rails at the other end of said stretch, and directional means controlled by said two track relays.

8. In combination with a stretch of railway 55 track intersected by a highway, an insulated joint in one rail at one side of the highway, an insulated joint in the other rail at the other side of the highway, said two joints defining a right-hand and a left-hand track section, a 60 source of current connected across the two rails from one rail of said left-hand section to the other rail of said right-hand section, an electrical connection between said one rail of the right-hand section with said other rail of the 65 left-hand section, two track relays each receiving energy from the rails at the respective end of said stretch, an interlocking relay, and circuits for said interlocking relay controlled by said two track relays.

ROBERT M. GILSON. 70
